(57) **CLAIM**

The ornamental design for a sword handle, as shown and described.

DESCRIPTION

FIG. 1 is a left side elevational view of a sword showing a sword handle of the present invention connected to a sword blade, the sword blade depicted in phantom lines which forms no part of the claimed design for this invention, the right, opposite, side of which is a mirror image thereof; FIG. 2 is an enlarged left side elevational view of the sword handle, the right, opposite, side of which is a mirror image thereof;

FIG. 3 is a rear elevational view of the sword handle; FIG. 4 is a front elevational view of the sword handle; and, FIG. 5 is a top plan view of the sword handle, of which the bottom plan view is a mirror image thereof.

The broken lines shown are for illustrative purposes only and form no part of the claimed design.
